UNITED STATES PATENT OFFICE.

FREDERICK K. WRIGHT, OF SYRACUSE, NEW YORK, ASSIGNOR TO THE STEAM GAUGE AND LANTERN COMPANY, OF SAME PLACE.

DESIGN FOR A BICYCLE-LAMP.

SPECIFICATION forming part of Design No. 27,224, dated June 15, 1897.

Application filed January 25, 1897. Serial No. 620,694. Term of patent 7 years.

To all whom it may concern:

Be it known that I, FREDERICK K. WRIGHT, a citizen of the United States, residing at Syracuse, in the county of Onondaga and State of New York, have invented and produced a new and original Design for Bicycle-Lamps, of which the following is a specification, reference being had to the accompanying drawing, forming a part thereof.

10 The accompanying drawing represents a side elevation of a lamp for bicycles and other vehicles embodying my design.

15 The leading feature of my design consists of an upright prismatic body arranged between surmounting and subjacent circular parts in connection with a dome consisting of an upwardly-tapering lower portion and an upwardly-flaring upper portion and also in connection with a flat circular base portion.

20 A is the body of the lamp, having the form of an upright nine-sided prism. a represents

a circular bead arranged near the upper end of the prismatic body, b a circular collar above the bead a, and B a circular dome surmounting the body and consisting of an upwardly-tapering lower portion b', an upwardly-flaring perforated gallery c, and a convex top plate d. e represents a circular bead arranged at the lower end of the prismatic body, and f a circular collar below said bead. G represents the flat circular base portion, and H the circular front portion, of the lamp.

What I claim is—

The design for a lamp, substantially as herein shown and described.

Witness my hand this 20th day of January, 1897.

FREDERICK K. WRIGHT.
